US00D857914S

(12) **United States Design Patent** (10) Patent No.: **US D857,914 S**
(45) Date of Patent: **** Aug. 27, 2019**

(54) **INSTRUMENT MODULE**

- (71) Applicant: **Siemens Healthcare Diagnostics Inc.**, Tarrytown, NY (US)
- (72) Inventors: **Daniel LiCalzi**, New York, NY (US); **Scott Salmon**, Tenafly, NJ (US); **Josh Hartl**, Philadelphia, PA (US)
- (73) Assignee: **Siemens Healthcare Diagnostics Inc.**, Tarrytown, NY (US)
- (**) Term: **15 Years**
- (21) Appl. No.: **29/632,899**
- (22) Filed: **Jan. 10, 2018**

Related U.S. Application Data

- (62) Division of application No. 29/569,389, filed on Jun. 27, 2016, now Pat. No. Des. 812,241.
